United States Patent Office

Des. 229,854

Patented Jan. 8, 1974

229,854

FLASHLIGHT

Harold F. Bajusz, Woodridge, N.J., assignor to Accutec,
Inc., Wallington, N.J.

Filed June 5, 1972, Ser. No. 260,053

Term of patent 14 years

Int. Cl. D26—02

U.S. Cl. D48—24 A

FIG. 1

FIG. 2

FIG. 3

FIG. 4

FIG. 5

FIG. 6

FIG. 1 is a perspective view of a flashlight showing my new design;

FIG. 2 is a front elevation view of the flashlight;

FIG. 3 is a side elevation view of the flashlight;

FIG. 4 is a top view of the flashlight;

FIG. 5 is a bottom view of the flashlight; and

FIG. 6 is a top view of a second embodiment of my design for a flashlight, the first and second embodiments being identical except for the top.

I claim:

The ornamental design for a flashlight, as shown and described.
